UNITED STATES PATENT OFFICE.

EDWARD R. LIST, OF ODIN, ILLINOIS.

DESIGN FOR A SHOE-POLISHER FRAME.

SPECIFICATION forming part of Design No. 28,659, dated May 17, 1898.

Application filed March 10, 1898. Serial No. 673,405. Term of patent 7 years.

To all whom it may concern:

Be it known that I, EDWARD R. LIST, a citizen of the United States, residing at Odin, in the county of Marion and State of Illinois, have invented and produced a new and original Design for Shoe-Polisher Frames, of which the following is a full, clear, and exact specification, reference being had to the accompanying drawing, forming part thereof, and in which the figure is a perspective view of my polishing-frame.

As shown in the drawing, the leading or material feature of my design consists of the main or body portion, having the middle portion A and the depending ends B and the upper projection extending in the direction of length of the middle portion A and having the handle-like representation C at one end

and the knob-like projection D at its other end.

The middle portion A is arched or curved from end to end on both sides, and the ends B drop from the middle A and have their inner faces formed on curves simulating the line of beauty and merging in the curved under sides of the middle portion A.

Having thus described my invention, what I claim as new, and desire to secure by Letters Patent, is—

The design for a shoe-polisher frame, as herein shown and described.

EDWARD R. LIST.
